ATTORNEY

UNITED STATES PATENT OFFICE.

JOHN MESNY TOURTEL, OF WATERTOWN, NEW YORK.

STROPPING DEVICE.

1,240,515.

Specification of Letters Patent. **Patented Sept. 18, 1917.**

Original application filed June 2, 1916, Serial No. 101,292. Divided and this application filed December 27, 1916. Serial No. 139,189.

To all whom it may concern:

Be it known that I, JOHN MESNY TOURTEL, a subject of the King of Great Britain, residing at Watertown, in the county of 5 Jefferson, State of New York, United States of America, have invented a new and useful Improvement in Stropping Devices; and I do hereby declare the following to be a full, clear, and exact description of the 10 same.

This invention relates to a stropping device particularly adapted to be used in machines for stropping razor blades of all kinds and other cutting blades.

15 The present application is a division of my co-pending application, Serial No. 101,292, filed June 2, 1916.

An object of this invention is to provide a stropping device suitable for use in conjunction with a similar stropping device for stropping both sides of the blade at the same instant, so that the cutting edge will not bend first to one side or the other or be left in bent condition.

25 It is, of course, understood that the device can also be used singly—that is, not in conjunction with a similar device; and another object is to provide an efficient stropping device used alone or not for all kinds 30 of cutting blades.

While my invention is described herein in detail, it is understood that various changes may be made in the construction without departing from the scope of the 35 invention as claimed.

In the accompanying drawing, which is for illustrative purposes only and not drawn to scale,

40 Fig. 1 is a side view of the device;
Fig. 2 is an end view;

Fig. 3 shows a section on line 3—3 of Fig. 1, and

Fig. 4 is a sectional view showing how two of these devices are used in conjunc-

tion to strop both sides of the blade at the 45 same instant.

Like reference numerals refer to like parts throughout the several views of the drawing.

The stropping device comprises a loop 5 50 of a suitable stropping material, for instance, leather, and a cylindrical elastic cushion 6 preferably of rubber or the like filling said loop.

The ends of the loop are laid upon each other and disposed around a spindle 7 and under a semi-cylindrical plate 8, the plate and loop ends being secured firmly on the spindle by means of screws 9 passing through said plate and ends.

60 A stropping device thus constructed is very efficient, particularly so when used in pairs to strop both sides of a blade 10 (Fig. 4), when the spindles 7 are rotated so as to cause the stropping cushions to pass in a 65 direction from the back toward the edge of the blade.

I claim as my invention:

1. A razor strop including a rotatable shaft, a leather strap folded upon itself 70 with the folded edges secured to one side of the shaft, and an elastic filling for the folded strap.

2. A razor strop including a rotatable shaft, a leather strap folded upon itself 75 with the folded edges secured to one side of the shaft, a reinforcing plate positioned at the point of connection with said shaft, and an elastic filling for said folded strap.

3. A razor strop including a rotatable 80 shaft, a leather strap folded upon itself with the folded edges secured to one side of the shaft, and a cylindrical elastic filling for the folded strap.

In testimony whereof I have signed my 85 name to this specification.

JOHN MESNY TOURTEL.
